RUG-CONTACTING GRILL FOR A VACUUM CLEANER NOZZLE OR THE LIKE

Raymond H. Fineberg, Elkins Park, and Robert B. Edelson, Dresher, Pa., and Richard E. De Sisto, Salem, Mass., assignors to Proctor-Silex Incorporated, Philadelphia, Pa.

Filed Aug. 2, 1971, Ser. No. 168,305

Term of patent 14 years

Int. Cl. D15—05

U.S. Cl. D7—170

FIG. 1 is an isometric view of a rug-contacting grill embodying our new design;

FIG. 2 is an elevational view of one side of the rug-contacting grill shown in FIG. 1;

FIG. 3 is a front elevational view of the rug-contacting grill shown in FIG. 1; and

FIG. 4 is a bottom plan view of the rug-contacting grill shown in FIG. 1.

We claim:

The ornamental design for a rug-contacting grill for a vacuum cleaner nozzle or the like, as shown.
